UNITED STATES PATENT OFFICE

PATRICK F. GORMAN, OF CENTRAL FALLS, RHODE ISLAND

AERIAL SAFETY SUIT DEVICE

Application filed May 7, 1931. Serial No. 535,742.

This invention relates to an aerial safety suit device, the general object of the invention being to provide means whereby a workman or other person can be raised and supported in a standing position while performing tasks which are so located that one must be supported in a sling or the like in order to perform them.

This invention also consists in certain other features of construction and in the combination and arrangement of the several parts, to be hereinafter fully described, illustrated in the accompanying drawings and specifically pointed out in the appended claim.

In describing the invention in detail, reference will be had to the accompanying drawings wherein like characters denote like or corresponding parts throughout the several views; and in which:

Figure 1 is an elevation of the device.

Figure 2 is an end view thereof or a view taken at right angles to Figure 1.

Figure 3 is a top plan view with the supporting means removed.

Figure 4 is a detail view of one end of the supporting beam.

In these drawings, the numeral 1 indicates a belt formed of any suitable material but preferably of solid woven cotton of four ply and having straps 2 and 2' connected to its ends, preferably by bolts 3, one belt strap having a buckle 4 attached to its end and the other strap being formed with a perforated tongue 5, the perforations of which are adapted to receive the prong of the buckle so that the belt can be adjusted around the waist of different persons.

A pair of loop straps 6, preferably of solid woven cotton, each has one end bolted or otherwise fastened to the front part of the belt 1 as shown at 7. The other end of each strap 6 is suitably fastened to the rear part of the belt adjacent the side so that these two straps 6 form slings for receiving the feet of the user who has the belt 1 fastened about his waist.

Four triangular shaped members 8 are fastened to the belt 1 either by the looped upper ends of the straps 6 as shown in Figure 2 or by separate looped parts connected with the

belt 1 and these members 8 are engaged by snap hooks 9 each pair of which is connected to the end of a flexible member 10 which passes through the opening 11 in a strap bracket 12 attached to each end of a beam 13 which has a centrally arranged bracket 14 thereon having an opening 15 in its top for receiving a hook attached to a hoisting cable or the like so that the entire device can be raised and lowered. This beam is reinforced by a metal bar 16 which passes through a groove in its lower edge as shown in Figures 2 and 4.

As shown in Figures 1 and 2 the hooks 9 of each flexible member 10 engage the pair of members 8 at one side of the belt.

From the foregoing it will be seen that I have provided a simple means for suspending a person engaging in aerial or off-ground work and which allows the user to stand in an upright position with the belt around his waist and his feet in the loops or slings 6.

It is thought from the foregoing description that the advantages and novel features of the invention will be readily apparent.

It is to be understood that changes may be made in the construction and in the combination and arrangement of the several parts, provided that such changes fall within the scope of the appended claim.

Having thus described my invention, what I claim as new is:

A device of the class described comprising a belt, adjustable means for fastening the belt about the waist of the user, a pair of vertically arranged looped straps forming slings and having their upper ends secured to the belt, each strap having one end connected to the belt forwardly of a side of the belt and its other end connected with the belt at the rear thereof and rearwardly of the said side of the belt, each strap having its ends bent to form loops with the looped parts extending above the belt and the fastening means for connecting the ends of the straps to the belt passing through the upper ends of the straps, the bent over portions and the belt, triangular shaped members placed in the loops formed by the bent over portions of the ends of the straps, a beam, brackets connected to

the ends thereof having openings therein, a flexible member passing through the opening of each bracket, snap fasteners connected with the ends of the flexible members and engaging the triangular shaped members, the snap fasteners of one flexible member engaging the triangular shaped members of one sling forming strap and the snap fasteners of the other flexible member engaging the triangular shaped members of the other sling forming member.

In testimony whereof I affix my signature.

PATRICK F. GORMAN.
